UNITED STATES PATENT OFFICE

2,669,948

SQUEEZE ROLLER APPARATUS

Joseph Francis Naylor, Newton-le-Willows, England; assignor to T. & T. Vicars Limited, Earlestown, Newton-le-Willows, England, a British company

Application October 30, 1951, Serial No. 253,817

Claims priority, application Great Britain
November 6, 1950

4 Claims. (Cl. 107—12)

1

The present invention relates to squeeze roller apparatus.

It is an object of the present invention to provide a squeeze roller apparatus wherein the minimum and maximum clearances between the squeeze rollers are readily adjustable and wherein the squeeze rollers may be locked at a minimum clearance.

According to the present invention in a squeeze roller apparatus, one of a pair of cooperating squeeze rollers is carried by blocks mounted in slideblocks, which slideblocks are displaceable towards and away from the other of said pair of squeeze rollers whereby to vary the minimum clearance between said rollers, said blocks being slidably mounted in said slideblocks and resiliently urged towards the said other of said pair of squeeze rollers, and adjustable stop devices being provided intermediate the slideblocks and the blocks whereby to vary the maximum clearance between said squeeze rollers.

The slideblocks are suitably displaceable by means of a manually rotatable wheel carried on the frame of the apparatus.

The adjustable stop devices suitably include threaded stop members carried by the slideblocks and displaceable relative to the slideblocks and relative to the blocks by means of a manually rotatable wheel carried on the slideblocks.

A locking pin carried by a slideblock is preferably displaceable from an inoperative position to an operative position to lock the block associated therewith.

The invention is further described by way of example with reference to the accompanying drawings, in which:

Fig. 1 is a side elevation, partly in section, of an apparatus according to the present invention, and

Fig. 2 is a corresponding end view.

In the drawing an upper squeeze roller 11 is mounted above a lower squeeze roller 12. The rollers are operatively connected by known means (not shown) to rotate the same. The upper squeeze roller is carried at one end by a block 13 slidably mounted in vertical guides in an upper roller slideblock 14. The upper roller slideblock 14 is itself slidably mounted in vertical guides in the frame 15 of the squeeze roller apparatus.

The vertical position of the upper roller slideblock 14 is adjustable by means of handwheel (not shown) on shaft 16. A bevel pinion 17 on shaft 16 is in engagement with a bevel wheel 18 carried at one end of a threaded member 19 ro-

2

tably connected to the frame 15. The threaded member 19 passes through a correspondingly threaded portion of the slideblock 14.

A spring 20 is interposed between the bridge 21 of the slideblock and a collar 24a on a threaded portion of a vertical projection 24 carried on the block 13. The block 13 is accordingly displaceable upwardly in the slideblock 14 against said spring. The upmost limit of displacement of the block 13 up to the slideblock is defined by an adjustable threaded stop member 22 which may be raised or lowered relative to the bridge 21 by means of a handwheel 23. The stop member 22 cooperates with the vertical projection 24. It will be seen that the tension of the spring 20 may be adjusted by means of the collar 24a.

A lever 25 is pivotably connected at its upper end to the slideblock. A locking pin 26 (shown in the locked position) is pivotably connected to the lever 25 and passes through projections from the slideblock 14 and a downwardly extending part 13a of the block 13. The lever 25 is pivotable by a foot-pedal (not shown) to displace the pin 26 into and out of the locked position.

It will be seen that the handwheel on shaft 16 controls the minimum clearance between the squeeze rollers 11, 12, and that the handwheel 23 controls the maximum clearance between the squeeze rollers 11, 12.

Both handwheels may be readily operated during operation of the apparatus.

It will be appreciated that whereas only a single lever 25, locking pin 26 and associated parts are shown, the block 13, slideblock 14 and parts associated therewith will be duplicated at the other side of this apparatus.

An apparatus according to the present invention may suitably comprise a dough break.

In order to reduce in thickness a slab of material (e. g. a slab of dough), the minimum and maximum clearances between the squeeze rollers are set by means of hand wheels 16 and 23 and the locking pin 26 is displaced out of the locked position. The slab of material is passed one or more times between the squeeze rollers, the weight of the upper squeeze roller 11 and the force of the springs 20 causing a reduction in thickness of the slab. As soon as the slab has been reduced to approximately the thickness of said minimum clearance, the pin 26 is displaced into the locked position to lock the squeeze rollers at said minimum clearance. A subsequent final passage of the slab between the squeeze rollers accordingly ensures uniform reduction in the thickness of the slab.

I claim:

1. In a squeeze roller apparatus, in combination a frame, a pair of slide blocks, a pair of blocks slidably mounted on the said slideblocks, a first squeeze roller carried in said blocks, a second squeeze roller, means to displace said slideblocks towards and away from said second squeeze roller whereby to vary the minimum clearance between the peripheral surfaces of said squeeze rollers, means to urge resiliently said blocks towards the second squeeze roller, and an adjustable stop device disposed intermediate a slideblock and a block whereby to vary the maximum clearance between said squeeze rollers.
2. In a squeeze roller apparatus, in combination a frame, a pair of slide blocks, a pair of blocks slidably mounted on the said slideblocks, a first squeeze roller carried in said blocks, a second squeeze roller, a manually rotatable wheel carried on said frame and operatively connected to said slideblocks to displace said slideblocks towards and away from said second squeeze roller whereby to vary the minimum clearance between the peripheral surfaces of said squeeze rollers, means to urge resiliently said blocks towards the second squeeze roller, and an adjustable stop device disposed intermediate a slideblock and a block whereby to vary the maximum clearance between said squeeze rollers.
3. In a squeeze roller apparatus, in combination a frame, a pair of slideblocks, a pair of blocks slidably mounted on the said slideblocks, a first squeeze roller carried in said blocks, a second squeeze roller, means to displace said slideblocks

5 towards and away from said second squeeze roller whereby to vary the minimum clearance between the peripheral surfaces of said squeeze rollers, means to urge resiliently said blocks towards the second squeeze roller, a stop member carried by a slideblock, and means to displace the stop member relating to a block whereby to vary the maximum clearance between said squeeze rollers.

- 10 4. In a squeeze roller apparatus, in combination a frame, a pair of slideblocks, a pair of blocks slidably mounted on the said slideblocks, a first squeeze roller carried in said blocks, a second squeeze roller, means to displace said slideblocks towards and away from said second squeeze roller whereby to vary the minimum clearance between the peripheral surfaces of said squeeze rollers, means to urge resiliently said blocks towards the second squeeze roller, an adjustable stop device disposed intermediate a slideblock and a block whereby to vary the maximum clearance between said squeeze rollers, a locking pin carried by a slideblock, and means to displace the locking pin from an inoperative position to an operative position to lock the block associated therewith.

25 JOSEPH FRANCIS NAYLOR.
